(57) **CLAIM**

The ornamental design for a decorative urn, as shown and described.

DESCRIPTION

FIG. 1 is a front, right, and top perspective view of a decorative urn, showing my design.
 FIG. 2 is a rear, left, and bottom perspective view thereof.
 FIG. 3 is a front elevation view thereof.
 FIG. 4 is a rear elevation view thereof.
 FIG. 5 is a left side elevation view thereof.
 FIG. 6 is a right side elevation view thereof.
 FIG. 7 is a top plan view thereof.
 FIG. 8 is a bottom plan view thereof; and,
 FIG. 9 is a partial enlarged view of an area labeled 9 in FIG. 1 comprising a part of a protrusion.
 The dot-dash-dot broken lines encircling portions of the decorative urn in FIG. 1 and illustrated in the enlarged view of FIG. 9 form no part of the claimed design.
